CLAIM

The ornamental design for a wireless communication interface, as shown and described.

DESCRIPTION

FIG. 1 is a perspective view of a wireless communication interface showing my new design;

FIG. 2 is a left side elevational view thereof;

FIG. 3 is a bottom plan view thereof;

FIG. 4 is a top plan view thereof;

FIG. 5 is a right side elevational view thereof;

FIG. 6 is a front elevation view thereof; and,

FIG. 7 is a rear elevational view thereof.

The broken lines which define the bounds of the claimed design form no part thereof.
